UNITED STATES PATENT OFFICE

1,995,176

ELECTRIC DISCHARGE APPARATUS

August Glaser, Berlin-Frohnau, Germany, assignor to General Electric Company, a corporation of New York

Application October 17, 1932, Serial No. 638,235
In Germany October 21, 1931

2 Claims. (Cl. 250—27)

The present invention relates to electric discharge apparatus, more particularly to hot cathode devices which contain gas or vapor and are energized by alternating current.

5 In devices of this sort when operated under these conditions, particularly in the case of the higher frequencies of energizing current, there is a tendency to form an arc-back on the inverse or negative half-cycle. The initiation of reverse 10 current is caused to a large extent by the presence of positive ions in the region of the anode which hold over from the forward or positive half-cycle.

An object of the present invention is to provide 15 an improved tube structure which causes an immediate absorption or neutralization of the positive ions during inverse so that arc-back is precluded. A tube improved in accordance with the invention is thus capable of withstanding considerably higher voltages than prior art devices, with consequent increased output and efficiency. In carrying out this object, an auxiliary electrode is provided near the anode and is charged to a higher negative potential than the anode during 20 the inverse portion of the alternating current cycle in order to attract the positive ions away from the anode and neutralize them. There is also provided a current-limiting resistance in series with the auxiliary electrode to prevent the latter from taking over the function of the main anode during the positive half-cycle. The invention will be more fully understood when reference is made to the following description and the accompanying drawing in which Fig. 1 shows diagrammatically the improved tube and an energizing circuit, while Fig. 2 illustrates a portion 25 of a modified form of tube.

In the drawing, numeral 1 designates the envelope of a tube containing a cathode which is shown as an indirectly heated member, a plate-like anode 2, an auxiliary electrode 3, and an electrostatic control member 4. The indirectly heated cathode is generically illustrated as a filamentary heater 5 in heat-responsive relation to a flat plate 6 which is electrically connected to one leg of the filament and preferably is coated with electronically active material to constitute the cathode proper. The electrodes 3 and 4 conveniently are made of perforated material and 30 extend transversely across the envelope, although it will be understood that these electrodes, as well as the anode 2 and the cathode 6, may take on any suitable configuration e. g. concentric cylinders, etc., depending upon the desired characteristics of the tube. The member 3, referred to

hereinafter as the "auxiliary electrode", is positioned near the anode for reasons which will appear presently. The envelope 1 contains an ionizable medium, such as inert gas (helium, argon or the like) or mercury (not shown) having a pressure under operating conditions sufficient to support an arc-like discharge at the impressed voltages.

5 The heater 5 is energized by a source of alternating current through the transformer 7, and the anode is connected to a source of current, preferably alternating current, through a transformer 8. One end of the secondary of transformer 8 is connected through a load broadly indicated by rectangle 9 to heater 5 and cathode 10 6, while the other terminal of the transformer is connected to the auxiliary electrode 3 through a fairly high impedance 10, resistance or the like, also generically indicated by a rectangle. The anode 2 is connected to an intermediate tap 11 on the transformer secondary. The grid or electrostatic control member 4 may be connected to a source of control impulses.

In operation, when the charge on the grid 4 is sufficiently positive or less negative, an arc or 15 glow discharge will be produced in the tube due to the potential applied to the anode 2. This arc is caused by the cumulative ionization of the gas or vapor in the tube, and when once the arc has started, the grid 4 loses control unless a 20 prohibitory negative charge is applied thereto. This loss of control extends through the positive half-cycle of the alternating current voltage. When the transformer voltage reverses so that the anode 2 becomes negative with respect to the 25 cathode and the arc goes out, control is restored to the grid which then determines when the arc 30 will start during the next positive half-cycle.

During the positive half-cycle when current 35 flow is established, the gas or vapor becomes ionized and the positive ions formed thereby, also the electrons emanated by the cathode 6, serve to reduce the impedance of the tube so that a large current flows at relatively low voltages. It has been found that when the voltage of the 40 energizing source reverses, i. e. during the negative half-cycle, some of the positive ions hold over from the previous positive half-cycle and tend to cause reverse currents, thereby reducing the translation efficiency of the device and in 45 extreme cases, causing damage to the tube.

In order to eliminate these positive ions and 50 in accordance with my invention, there is provided the auxiliary electrode 3 which as stated hereinbefore, is connected to one of the outer 55

terminals of the transformer. During the negative half-cycle, this electrode becomes more negative than the anode when considered with respect to the cathode. It is apparent that under these conditions, the highly negative electrode 3 will immediately absorb the positive ions which reside in the region of the anode at the beginning of the negative half-cycle and consequently, will prevent ionization of the gas or vapor taking place when the anode is negative with respect to the cathode. In order that the auxiliary electrode 3 may not itself give rise to the production of positive ions on account of its high potential with respect to the anode 2 and the cathode 6, there may be provided in the auxiliary electrode circuit, a current-limiting resistance 10. The space between the auxiliary electrode 3 and the anode 2 is preferably less than the free mean path of electrons in the space, which further reduces the possibility of glow discharge occurring between electrodes 2 and 3.

It is apparent that since the auxiliary electrode 3 immediately and completely removes the positive ions left in the envelope when the voltage of the energizing current source crosses the zero voltage axis and starts on the inverse half-cycle, the impedance of the tube which was considerably reduced during the formation of the arc or glow discharge, is now increased and remains at a high value throughout the remainder of the cycle. Consequently, the tube efficiently conducts current in the positive direction, i. e. when the anode is positive, but constitutes a substantially open circuit when the anode is negative.

It is also apparent that since the auxiliary electrode 3 is connected to the same secondary winding as the anode 2, the voltages applied to these two electrodes are in phase, so that the auxiliary electrode 3 becomes highly negative with respect to the cathode 6 at the same moment that the anode 2 is also negative. Since this phase relation remains the same, the frequency of the alternating voltage applied to the anode may be increased indefinitely without any substantial reduction of the efficiency with which the auxiliary electrode operates. In some cases, it may be advantageous to provide in the auxiliary electrode circuit, an adjustable direct current voltage, obtained, for example, from a battery (not shown) in order that the time in the voltage cycle at which the auxiliary electrode absorbs the positive

ions may be more accurately determined. However, it has been found that ordinarily, the auxiliary electrode may be connected directly to the transformer secondary through the non-adjustable high resistance 10.

While I have described my invention in connection with an electrostatically controlled arc discharge device employing an indirectly heated cathode, it is to be understood that the invention is not limited to this structure but applies equally well to a two-electrode rectifier without a control member and also to a device which employs a directly heated or even a cold cathode.

In Fig. 2, the auxiliary electrode takes the form of a hollow cylinder 12 secured in the glass stem 13 of the envelope 1 in any suitable and well-known manner. The cylinder 12 is provided at its end facing the cathode with a perforated metal plate 14 which, together with the cylinder, serves the purpose of absorbing the positive ions held over from the positive half-cycle. Leading-in conductors 15 and 16 may be taken respectively from the anode and the cylinder to the exterior, for connection to the secondary of an energy supply transformer as explained hereinbefore.

What I claim as new and desire to secure by Letters Patent of the United States, is:

1. In combination, an electric discharge device comprising an envelope containing a cathode, an anode and an inert gas at a pressure sufficient to support an arc-like discharge at the impressed voltages, an auxiliary electrode positioned in the region of said anode, an alternating current supply transformer, the outer terminals of said transformer being connected respectively to said cathode and said auxiliary electrode, and a connection between an intermediate tap on said transformer and the anode.

2. In combination, an electron discharge device comprising an envelope containing a cathode, an anode, an ionizable medium at a pressure sufficient to support an arc-like discharge at the impressed voltages, and a hollow auxiliary electrode substantially enclosing said anode and spaced therefrom at a distance less than the free mean path of electrons in the space, said electrode being charged to a greater alternating current potential than the anode but having substantially the same polarity of potential.
